ELECTRICAL RECEPTACLE

William F. McIntosh, Charlestown, Mass.

Application January 7, 1935, Serial No. 676

1 Claim. (Cl. 173—334)

My present invention relates to receptacles and more particularly to electrical portable receptacles.

The principal object of my invention is an improved electrical receptacle.

Another object is a portable electrical receptacle which is particularly adaptable for heavy duty work.

Another object is a portable electrical receptacle having a multiplicity of plug outlets.

Other objects and novel features comprising the construction and operation of my invention will appear as the description of the same progresses.

In the drawing illustrating the preferred embodiment of my invention,

Fig. 1 is a side elevation of the receptacle.

Fig. 2 is a side elevation of the central portion of the receptacle with the near side removed.

Fig. 3 is a cross section taken on the line 3—3 of Fig. 1.

Fig. 4 is a side elevation taken at ninety degrees to Fig. 1.

Fig. 5 is a detailed perspective view of one the contact bar ends to which is connected an electrical cable wire.

Referring more in detail to my invention, 10 and 11 indicate two duplicate halves comprising the base of the receptacle. 12 and 13 indicate two duplicate halves comprising the insulated casing surrounding the receptacle inlets, solidly anchored in the base of 10 and 11 by means of a screw 14 which passes through bosses 15 and 16 formed on the inner surface of base members 10 and 11 and seated in recesses 17 and 18 in the sides of the insulated members 12 and 13 respectively.

On the inner face of the casing 12 and 13 are grooves 19 and 20. One groove on each block is deeply recessed at 21 and the other block is recessed in the same manner as shown at 22 which is directly over the groove 20 in the member 12. These recesses are for the purpose of providing clearance for the end of the electrical contact bars 23 and 24 which have a raised portion 25 as shown in Fig. 5, and are recessed out at 26 for the purpose of admitting a screw 27 as shown in Fig. 3.

The electrical cable 26 is connected by the electrical conductor wire 27 to the bars 23 and 24 as follows; the ends of the electrical wires 27 are entered through the opening 28 in the bars 23 or 24 and pushed around the cylindrical sides of the recess 26 and under the head of the contact screws 27, the opening 28 being located at one side of the screw center more clearly indicated

in Figs. 2 and 5. The cable openings in the base members 10 and 11 are provided with annular rings 29, the inner periphery of which are considerably smaller in diameter than the normally rubber covered cable 26 and after the two halves 10 and 11 of the base member are firmly clamped together as shown in the drawing at Figs. 2 and 3, the annular rings become embedded in the rubber covering of the cable 26 such that it cannot be accidentally removed without releasing 10 the screws holding the base members together.

The outlet bars 23 and 24, one of which is shown in cross section in Fig. 3 comprises a strap body portion and a series of outlets disposed thereon oppositely. One half of the bar proper is embedded in one of the grooves of the insulating block as at 19 or 20, and the top half being likewise embedded in similar corresponding grooves in the other half of the insulating block.

The outlet receptacles are indicated at 31, the construction of which is clearly shown in Fig. 3, there being provided slots 34 for the purpose of establishing spring contacts with the plug points of an electrical plug not shown.

The insulated members 12 and 13 are recessed at 35 and 36 to provide openings in which the receptacle portions 31 are located together with the plug opening 36. The bottom half of the casing 12 is further provided with a recess 37 and also a semi-recess 38 located in the surface 30 of both members 12 and 13 for the purpose of admitting a hooked member 39 which when assembled in the casing 13 as shown in Figs. 1, 3, and 4 becomes firmly embedded therein. The casings 12 and 13 are normally held together by means of screws 40 extending from side to side of the members 12 and 13.

While I have shown a particular application of my invention, it is to be understood that various modifications may be resorted to while still continuing to adhere to the original spirit of my invention.

Having thus described my invention, what I claim is:

An electrical plug receptacle comprising in combination, a symmetrical multiple electrical plug bar having a plurality of split bosses oppositely opposed to each other on either side of said bar, one end of said bar being provided with a hollow binding post boss, symmetrical casings enclosing 50 said bar and being provided on their inner opposed sides with counterbored plug openings the counterbored portion being adapted to receive the said split bosses on said plug bar, symmetrical housings having locking bosses oppositely op- 55

posed on the inner sides thereof and adapted to fit into counterbored recesses provided for the purpose on the outside and adjacent one end of said casings, a clamping screw adapted to pass through said locking bosses and casings for the purpose of binding said housing together about said casings and an electrical cable connecting

with said plug bar, a recess located on the inside face of one of said casings, a hook member having one end bent at forty-five degrees for the purpose of anchoring said hook member in said recess in said casing.

5 WILLIAM F. MCINTOSH.
